US00D776675S

(12) **United States Design Patent** (10) Patent No.: **US D776,675 S**
(45) Date of Patent: ** Jan. 17, 2017

(54) **CONTROL UNIT FOR AIR COMPRESSOR
WITH GRAPHICAL USER INTERFACE**

(71) Applicant: **Hitachi Industrial Equipment Systems Co., Ltd.**, Chiyoda-ku, Tokyo (JP)

(72) Inventors: **Hiroshi Ohta**, Tokyo (JP); **Akira Iyozumi**, Tokyo (JP); **Hiroyuki Matsuda**, Tokyo (JP); **Takashi Nakajima**, Tokyo (JP); **Hayato Adachi**, Chiba (JP); **Hideharu Tanaka**, Tokyo (JP); **Kazumasa Kanai**, Tokyo (JP); **Zhijia Ren**, Tokyo (JP)

(73) Assignee: **Hitachi Industrial Equipment Systems Co., Ltd.**, Tokyo (JP)

(**) Term: **14 Years**

(21) Appl. No.: **29/519,023**

(22) Filed: **Mar. 2, 2015**

(30) **Foreign Application Priority Data**

Sep. 3, 2014 (JP) 2014-019388

(51) LOC (10) Cl. 14-04

(52) U.S. Cl.

USPC **D14/485**

(58) **Field of Classification Search**

USPC D14/485-495

CPC G06F 3/04817; G06F 3/0482

See application file for complete search history.

(57) **CLAIM**

The ornamental design for a control unit for air compressor with graphical user interface, as shown and described.

DESCRIPTION

The FIGURE is a front view of a control unit for air compressor with graphical user interface showing our new design.

The broken line showing of the control unit and the remainder of the graphical user interface forms no part of the claimed design.

1 Claim, 1 Drawing Sheet
